(57) **CLAIM**

The ornamental design for an oval decorative vehicle lighting lens with stepped interior surface, as shown and described.

DESCRIPTION

FIG. 1 is a perspective view of an oval decorative vehicle lighting lens with stepped interior surface, showing my new design;

FIG. 2 is a bottom plan view thereof;

FIG. 3 is a top plan view thereof;

FIG. 4 is a side elevational view thereof, the other side being identical;

FIG. 5 is an end elevational view thereof, the other end being identical; and,

FIG. 6 is a perspective view thereof, showing my new design in its position of use, it being understood that the broken line (showing the mounting ring of the vehicle lighting) is for illustrative purposes only and forms no part of the claimed design.
